UNITED STATES PATENT OFFICE.

CHARLES SYLVESTRE, OF WINNIPEG, MANITOBA, CANADA.

GAS-CONTROLLING DEVICE FOR LINOTYPE-MACHINES.

1,396,705.

Specification of Letters Patent. Patented Nov. 8, 1921.

Application filed April 16, 1918. Serial No. 228,985.

(GRANTED UNDER THE PROVISIONS OF THE ACT OF MARCH 3, 1921, 41 STAT. L., 1313.)

To all whom it may concern:

Be it known that I, CHARLES SYLVESTRE, of the city of Winnipeg, in the Province of Manitoba, Canada, have invented certain new and useful Improvements in Gas-Controlling Devices for Linotype-Machines, of which the following is the specification.

The invention relates to improvements in gas controlling devices for linotype machines and the principal object of the invention is to provide an appliance which will automatically control the supply of gas fed to the pot gas burner and the mouth burner and dependent on the temperature in the pot and in the mouth piece of the linotype machine.

A further object of the invention is to construct an appliance with the above object in a simple, durable and inexpensive manner and such that it can be readily applied to a machine.

A further object is to construct the appliance so that it can be regulated to be particularly sensitive to slight temperature changes.

With the above general and other objects in view, which will become more apparent as the description proceeds, the invention consists essentially in the arrangement and construction of parts hereinafter more particularly described and later pointed out in the appended claims, reference being had to the accompanying drawings in which:—

Figure 1 represents an end view of the device as applied on the pot and mouth piece of a linotype machine.

Fig. 2 represents an enlarged detailed side view of the device as removed from the machine and with the connecting pipes detached.

Fig. 3 represents an inverted plan view of the device as it appears in Fig. 2.

Fig. 4 represents a longitudinal vertical sectional view through the device.

Fig. 5 represents a face view of the central valve member.

Fig. 6 represents a longitudinal sectional view through the central and through one of the end members of the valve, the section being taken in the plane denoted by the line X—X' Fig. 5.

Fig. 7 represents a longitudinal sectional view through the central valve member, the

section being taken in the plane denoted by the line Z—Z' Fig. 5.

Fig. 8 represents a vertical sectional view through the central valve member, the section being taken in the plane denoted by the line Y—Y' Fig. 6.

In the drawings like characters of reference indicate corresponding parts in the several figures.

1 represents the pot of an ordinary linotype machine in which the metal is melted prior to being expelled through the customary mouth piece 2 associated with the pot. The metal of slugs placed in the pot are melted by the heat generated by the pot gas burner 3 and the metal expelled through the mouth piece is further heated by the heat generated by a gas burner 4 termed the pot mouth burner.

The gas to these burners is supplied by the gas pipes 5 and 6. Within the pot a mercury thermometer 7 is placed, this being connected to a mercury pipe 8 and a second mercury thermometer 9 is inserted in the mouth piece and is connected to a mercury pipe 10.

The above parts are all of ordinary construction and are found on the majority of existing linotype machines. Accordingly I have not considered it necessary to further enlarge on the details of such parts as for a complete understanding of my invention, which relates to the controlling of the gas fed to the two burners and dependent upon temperature, it is only necessary to control the gas fed in the pipes 5 and 6 directly in accordance with the temperatures in the crucible and mouth piece and as indicated by columns of mercury in the pipes 8 and 10.

The appliance which I provide is actually an automatic valve connected with the gas pipes and mercury pipes and with a gas feed pipe and arranged in such a manner that the pressures of the mercury in the pipes 8 and 10 operate directly to shut off or admit of the feed of gas from the main feed pipe to the pipes 5 and 6, the amount of gas admitted to these pipes being directly in proportion to the pressure of the mercury in the pipes 8 and 10 respectively.

The valve indicated generally by the reference numeral 11 is now described in detail.

It comprises three main body parts, a cen-

tral member 12 and two similar (right and left) end members 13 and 14, the end members being securely fastened to the central member by means of pairs of side bolts 15 and 16 provided.

The central member is bored centrally and longitudinally to provide an inlet duct 17 passing from face to face of the central member and connected by means of a radiat-

10 ing duct 18 with the main gas feed pipe 19. The opposing faces of the central member are machined to provide valve chambers 20 and 21 and valve seats 22 and 23 at the ends of the duct 17.

15 24 and 25 are gas outlet passages positioned at diametrically opposite sides of the central member 12, one communicating with the chamber 20 outside the valve seat 22 and the other with the chamber 21 outside the 20 valve seat 23. The outer end of the passage 24 communicates directly with the gas pipe 6 leading to the pot mouth burner while the outer end of the passage 25 connects directly with the pipe 5 leading directly to the 25 pot gas burner.

26 and 27 are disk valves adapted to seat on the valve seats and to the inner face of which I secure, as by soldering, coiled springs 28 and 29, the springs having their inner 30 ends seated on a cross web 30 positioned in the duct 17 at the juncture of said duct with the duct 18.

At this point I wish it to be understood that this cross web must not obstruct the 35 free passage of gas from the duct 17 to that 18.

The springs 28 and 29 not only support the valves but they hold them normally unseated as shown in Figs. 4 and 6.

40 The end members of the valve are identical in construction so I have only considered it necessary to describe one of them.

Each end member is formed with two extensions 31 and 32 positioned at right angles 45 one to the other and each bored to provide two intersecting passages 33 and 34. The outer end of the passage 34 is interiorly screw threaded to receive an adjusting screw 35 while the inner end of the passage 50 opens to a chamber 36 formed in the face of the end member and separated from the adjoining chamber in the central member by a diaphragm 37 which is jammed between the end member and the central member 55 when the same are fastened together by the bolts 15 and 16.

It will be here noticed that the passage 33 is formed by boring completely through the end member and then closing the upper 60 end of the passage by a screw plug 38. The plug allows of filling with mercury from time to time as occasion may require.

At this point I wish it to be distinctly understood that there are two diaphragms, 65 one dividing each of the internal chambers

provided between the central member and the end members.

The valves 26 and 27 herein before disclosed are held by the springs normally against the inner face of the diaphragms. 70 The diaphragms are preferably made from a material such as leather which is flexible and will allow of bulging under pressure.

The open end of the passage 33 in the member 13 is connected directly with the 75 mercury pipe 10 while the open end of the passage 33 of the member 14 is directly connected with the mercury pipe 8.

The above completes the description of the parts but in order that the operation of the 80 device may be better understood I will now describe the manner in which it is used, assuming that under normal set conditions the temperatures developed in the crucible and in the mouth piece are such that the dia- 85 phragms take the positions as shown, being held in these positions by the pressure of the mercury on one side acting against the pressure of the spring on the other. Obviously the mercury columns maintained in 90 the pipes 8 and 10 and in the passages 33 and 34 and cavities 36 exert an inward pressure on the outer faces of the diaphragms which is counter-acted by the spring pressure exerted against the inner faces of the dia- 95 phragms through the disks.

Upon the temperatures rising in the crucible or in the mouth piece or both the mercury rising in the pipes will increase the pressure against one or other of the dia- 100 phragms or both, as the case may be, which action will cause the diaphragms to bulge toward the disks and in so doing they will cause the disks to close in against the action of the springs and toward the valve seats 105 and thereby reduce the feed of the gas in passing from the duct 17 to the outlet ports 24 and 25. This reduction of the gas fed will result directly in a decrease of the heat applied to the crucible and to the mouth piece so that upon an increase in temperature above normal in either the crucible or mouth piece there is a reduction in the amount of gas fed to these members. 110

Conversely it will be obvious if such a condition arises that a reduction in the temperature in either the crucible or mouth piece will give an increased feed of gas, for heating purposes, to either the crucible or the mouth piece. 115

From the above it will be apparent that this appliance controls independently both the crucible and the mouth piece as the dia- 120 phragms operate independently one of the other and directly as the result of the pressure of the mercury in the pipes leading to such parts.

If at any time it is desired to make the appliance more or less sensitive this can be done by screwing in or out the adjusting screws 130

35 which action will vary the space containing the mercury columns and will consequently increase or decrease the pressure of the mercury on the diaphragm.

5 Normally these screws will be set to give what might be termed a full gas feed at normal operating temperatures.

What I claim as my invention is:—

1. In a type setting machine, the combination with a metal pot, the mouth piece thereof, the gas pipe leading to the pot and the mouth piece and the mercury pipes associated with the pot and mouth piece and a gas supply pipe, of a gas controlling device 10 inserted between the gas supply pipe and the gas and mercury pipes of the pot and mouth piece and provided with a pair of valves and internally arranged such that the varying pressure of the mercury in the pot mercury pipe controls, through one valve, the feed of gas from the supply pipe to the pot gas pipe and the varying pressure of the mercury in the mouth piece mercury pipe controls through the other valve the feed of gas from 15 the supply pipe to the mouth gas pipe.

2. In a type setting machine, the combination with the metal pot, the mouthpiece thereof, the gas pipes leading to the pot and the mouth piece and the mercury pipes associated with the pot and mouth piece and a gas supply pipe, of a gas controlling device 20 inserted between the gas supply pipe and the gas and mercury pipes of the pot and mouth piece and presenting a gas inlet passage 25 connected with the gas supply pipe, separate interior chambers to which the gas inlet passage leads and having valve seats located at the entrances of the passage to the chambers, a diaphragm crossing each chamber and dividing each chamber into two distinct inner and outer compartments, a normally open 30 valve opposite the valve seat and to the inner side of the diaphragm, inlet passages connecting the outer compartments one with the mercury pipe of the pot and the other 35 with the mercury pipe of the mouth piece and passages connecting the inner compartments one with the gas pipe of the pot and the other with the gas pipe of the mouth 40 piece.

3. In a type setting machine, the combination with the metal pot, the mouth piece thereof, the gas pipe leading to the pot and the mouth piece and the mercury pipes associated with the pot and mouth piece and a gas supply pipe, of a gas controlling device 45 inserted between the gas supply pipe and the gas and mercury pipes of the pot and mouth piece and presenting a gas inlet passage 50 connected with the gas supply pipe, separate interior chambers to which the gas inlet passage leads and having valve seats located at the entrances of the passage to the chambers, a flexible diaphragm crossing 55 each chamber and dividing it into two com-

partments, one for gas and the other for mercury, a displacer, a spring pressed valve opposing the valve seat in each instance and normally engaging the inner face of the displacer, a connection between one of the 70 mercury compartments and the mercury pipe of the pot, a connection between the other of the mercury compartments and mercury pipe of the mouth piece, a connection between one of the gas compartments and 75 the gas pipe of the pot and a further connection between the other of the gas compartments and the gas pipe of the mouth piece.

4. A gas controlling device for type setting machines comprising a valve casing presenting two inner valve chambers, flexible diaphragms crossing the chambers and dividing them each into two distinct inner and outer compartments, a gas supply passage 80 communicating with both the inner compartments, valve seats located at the entrance ends of the said passage and in a location directly opposite the diaphragm, distinct gas outlet passages leading from the 85 inner compartments, distinct mercury inlet passages communicating with the outer compartments and a valve normally opposing each valve seat and engaging the diaphragm.

5. A gas controlling device for type setting machines comprising a valve casing presenting two inner valve chambers, flexible diaphragms crossing the chambers and dividing them each into two distinct inner and outer compartments, a gas supply passage 90 communicating with both the inner compartments, valve seats located at the entrance ends of the said passage and in a location directly opposite the diaphragm, a 95 valve opposing each valve seat, a compression spring operating on each valve and holding it normally unseated and against the diaphragm, distinct gas outlet passages leading from the inner compartments and distinct mercury inlet passages communicating with the outer compartments.

6. A gas controlling device for type setting machines comprising a valve casing presenting two inner valve chambers, flexible diaphragms crossing the chambers and dividing them each into two distinct inner and outer compartments, a gas supply passage 100 communicating with both the inner compartments, valve seats located at the entrance ends of the said passage and in a location directly opposite the diaphragm, a 105 valve opposing each valve seat, a compression spring operating on each valve and holding it normally unseated and against the diaphragm, distinct gas outlet passages leading from the inner compartments, distinct mercury inlet passages communicating with the outer compartments and adjustable 110 means for varying the capacity of the mercury passages.

7. A gas controlling device for type setting machines comprising a valve casing presenting two inner valve chambers, flexible diaphragms crossing the chambers and dividing them each into two distinct inner and outer compartments, a gas supply passage communicating with both the inner compartments, valve seats located at the entrance ends of the said passage and in a location directly opposite the diaphragm, a valve opposing each valve seat, a compression spring operating on each valve and holding it normally unseated and against the diaphragm, distinct gas outlet passages

leading from the inner compartments, distinct mercury inlet passages communicating with the outer compartments and an adjusting screw operating in each mercury passage and permitting of the varying of the quantity of mercury admitted to the interior of the gas controlling device. 15
